United States Patent Office.

NATHANIEL FAIRBROTHER AND GEORGE S. FALES, OF PAWTUCKET,
RHODE ISLAND.

Design No. 2,568, dated February 5, 1867.

DESIGN FOR A TRADE-MARK.

The Schedule referred to in these Letters Patent and making part of the same.

TO ALL WHOM IT MAY CONCERN:

Be it known that we, NATHANIEL FAIRBROTHER, and GEORGE S. FALES, both of Pawtucket, in the State of Rhode Island, have originated and designed a new Design for a Trade-Mark; and we do hereby declare that the following is a full, clear, and exact description thereof, reference being had to the accompanying drawing, making part of this specification.

The trade-mark is intended to be stamped upon sides of leather manufactured by the undersigned, and to distinguish that variety of leather tanned by them as licensees under the patent granted to Moses W. Page, dated May 8, 1866.

It consists of the figure of a star drawn in outline, each angle of the outline forming the parts of the figure enclosing a dot; the central blank space being occupied with the words "Page's Patent, May 8, 1866."

What we claim as our invention, and desire to secure by Letters Patent, is—

The new design for a trade-mark herein shown and described.

NATHANIEL FAIRBROTHER,
GEORGE S. FALES.
